UNITED STATES PATENT OFFICE.

TRUWORTHY BROWN, STANLEY T. BROWN, AND EDWIN M. BROWN, OF BRUNSWICK, MAINE.

PLANING-MACHINE.

SPECIFICATION forming part of Letters Patent No. 243,204, dated June 21, 1881.

Application filed May 7, 1881. (Model.)

To all whom it may concern:

Be it known that we, T. BROWN, S. T. BROWN, and EDWIN M. BROWN, citizens of the United States, residents of Brunswick, in the county 5 of Cumberland and State of Maine, have invented a new and valuable Improvement in Planing-Machines; and we do hereby declare that the following is a full, clear, and exact description of the construction and operation 10 of the same, reference being had to the annexed drawings, making a part of this specification, and to the letters and figures of reference marked thereon.

Figure 1 of the drawings is a representation 15 of a longitudinal section. Fig. 2 is a horizontal section, and Fig. 3 is a detail view.

This invention has relation to means for planing timber before its removal from the saw-carriage; and it consists in the construction 20 and novel arrangement, in connection with a base provided with slideways and driving-gear, of an upright planer-shaft, its bracket-carriage movable on said ways, its fixed screw, and the nut-gear moving thereon, and pivoted 25 to an arm secured to the base, all as hereinafter shown and described.

In the accompanying drawings, the letter A designates the base, which is designed to be cast of iron, and is securely bolted to the floor 30 or foundation. The height of the base is sufficient to bring its top about even with the bed-timbers of the carriage on which the timber is sawed. It is designed to be placed before the circular or board saw in front of the saw- 35 yer, and the machine is operated in conjunction with the saw-mill carriage usually, although a special feeding-carriage may be used therewith. The upper part of the base is provided with slideways B, on which the planer-carriage C 40 moves. This carriage is provided with an upright standard, D, having bearings a for the upright planer-shaft E, carrying the cutter-head F, and on each side thereof bearings b for the face-rolls G. These rolls are usually provided 45 with springs in rear, allowing them play back and forth, if the work be very twisting. Below, an arm, H, extends downward through the carriage, and is provided with a bearing, e,

for the lower end of the planer-shaft, which carries the driving-pulley d. The base A is 50 made hollow, and into it extend from the planer-carriage downward the arms K, which are provided with squared bearings e for the squared ends g of the screw L, which is designed to have a fixed relation to the planer-carriage. On the screw is arranged the revolving nut N, which is provided with a gear-flange, h, and is pivoted in a bearing-arm, k, which is secured to the wall of the base. Through a bearing, l, in said wall extends the 60 driving-shaft m, which is provided with a gear, n, designed to engage the toothed flange of the nut N, operating to revolve the same, causing the screw L to move endwise, and with it the planer-carriage, in either direction. 65

The operation is as follows: After the timber has been sawed, if it is desired to subject it to the action of the planer, it is left on the saw-carriage, which is brought back. Then the driving-shaft m of the planer is turned, 70 moving the cutter-head and its gage-rolls out to the face of the timber, and the latter is moved by a forward action of the saw-mill carriage past the planer, so that it is fed thereto. After the timber has been planed on 75 one side the carriage on which it rests is run back and the work turned and planed on another side. This action is continued until all sides of the stick have been planed.

By means of this machine very heavy timber can be planed, finishing it smoothly and taking out the twist. After finishing the planing the planer-carriage C is moved back out of the way. Another log can then be put on the saw-mill carriage to be fed to the saw, 85 after which the planer-carriage can be moved up and the surface of the log dressed, as before described. If there is sufficient power, the log can be sawed and planed at the same time. The machine is designed to save a great 90 deal of time and labor in dressing heavy timber.

Having described this invention, what we claim, and desire to secure by Letters Patent, is—

1. The combination, with the base and

its slideways and the driving-gear *n*, of the endwise-moving planer-carriage, the upright planer-shaft, screw *L*, nut-gear *N*, cutter *F*, and rolls *G*, substantially as specified.

5 2. The combination, with the base and its slideways, of the reciprocating planer-carriage, its upright shaft, cutter, and rolls, substantially as specified.

In testimony that we claim the above we

have hereunto subscribed our names in the 10 presence of two witnesses.

TRUWORTHY BROWN.
STANLEY T. BROWN.
EDWIN M. BROWN.
